UNITED STATES PATENT OFFICE.

FRANCIS J. STALLINGS, OF EFFINGHAM, ILLINOIS.

RUNNING-GEAR FOR MOTOR-VEHICLES.

SPECIFICATION forming part of Letters Patent No. 708,844, dated July 1, 1902.

Application filed August 31, 1901. Serial No. 73,992. (No model.)

To all whom it may concern:

Be it known that I, FRANCIS J. STALLINGS, a citizen of the United States of America, residing at Effingham, in the county of Effingham and State of Illinois, have invented certain new and useful Improvements in Running-Gear for Motor-Vehicles, of which the following is a specification.

My invention relates to an improvement in running-gear for motor-vehicles, the object being to provide means for changing the speed through the changing of the gearing, and, further, to accomplish this by means of simple but strong and substantial mechanical instrumentalities. By this means I am enabled to change the speed of rotation of the driving mechanism from a low to a high speed, or vice versa, or by throwing the speed-changing mechanism to an intermediate position I can permit the motor-vehicle to coast down a declivity.

With these objects in view my invention consists in certain novel features of construction and combinations of parts which will be hereinafter described, and particularly pointed out in the claims.

In the accompanying drawings, Figure 1 is a plan view of a motor-vehicle provided with my improvements. Fig. 2 is a longitudinal 30 sectional view of one of the speed-changing gears with the clutch mechanism applied thereto. Fig. 3 is an end plan view of the gripping-jaws for operating the clutch on the speed-changing gear. Fig. 4 is a view of the shifting mechanism for operating the clutch, and Fig. 5 is a modification.

A represents the rear axle, journaled and turning in the frame B, and C is the motor, of any desired construction. A shaft 1, journaled in the frame B, is provided with cranks 2 2 therein, to which pitmen 3 3, operated by the motor, are connected. On either side of the cranks gear-wheels 4 and 5 are keyed to the shaft and revolve therewith. The dimensions of these gears are preferably three and six inches, respectively; but the size may of course be varied at convenience.

Driving-shaft 7 is journaled in the frame B at a little distance from shaft 1, and loosely 50 mounted on this driving-shaft are two gear-wheels 8 and 9, the former being of larger

size than the latter, in dimensions one preferably being about twenty inches and the other seventeen inches, and while these sizes, of course, might be varied the dimensions 55 given represent preferred relative sizes for attaining the two speeds. While these are referred to as "gear-wheels," they might, of course, be in the form of sprocket-wheels where sprocket-wheels are desirable. The 60 gear-wheels 8 and 9 mesh, respectively, with gear-wheels 4 and 5, it will be understood.

On the inner faces of gear-wheels 8 and 9 circumferentially-grooved rims 10 10 are cast integral therewith, or disks may be employed 65 in place of the rims, the disks secured or cast to the wheels. Clutch-bands 12 12 are fitted to these grooved rims, which clutch-bands may be of spring metal and constructed of one piece, having loops 13 formed at their adjacent ends.

Secured to the driving-shaft 7, near the gear-wheels 8 and 9, are brackets 14 14, their outer ends extending slightly above the plane of the circumference of grooved disks or rims 75 10 10, and on the apex of these brackets are pivoted jaws 11 11, approximately at their longitudinal centers, although this is not essential, the outer ends of each pair of jaws being received, respectively, in each of the loops 13 13 of the clutch-bands 12. To the shaft is also keyed a sleeve 15, which is adapted to slide thereon in a keyway 16 and is located intermediate the disks 10 10. The ends of this sleeve are enlarged to afford seats for 80 springs 31, the opposite ends of the springs bearing against the stationary brackets 14. The sleeve 15 is provided with arms 15', and the upper ends 29 of these arms are formed upon one side in a wedge shape, as shown, 90 which wedge-shaped side is adapted to be forced between the pivoted jaws 11 11, thereby causing the opposite ends of the jaws which are received and retained in the loops 13 13 of the clutch-band to be drawn together 95 to cause the clutch-band to grip the grooved disks 10 10, and thereby lock the grooved disk and the gear-wheel to which it is secured to the shaft, so that the shaft and wheel revolve together. Shoulders 30 are formed 100 on the arm to prevent any displacement of the free ends of the jaws 11 11. The springs

- 31 of course operate to force the arms of the sliding sleeve 15 out of contact with the free ends of the jaws when the speed-changing gear is operated.
- 5 The sliding sleeve 15 has formed thereon and centrally thereof an annular grooved seat 17. Thus when the sleeve is shifted toward one or the other of the gear-wheels the clutch-bands are drawn securely upon the 10 rims of the gear-wheels 8 or 9 by means of jaws 11 11, whose outer ends are drawn together, owing to the spreading apart of their inner ends by the sliding arms 15', thus locking the gear-wheels securely to the shaft 7.
- 15 Of course it is understood that the gear-wheels are far enough apart so that one is released when the other is secured to the shaft, and while one is always loose, on the other hand, by shifting the sleeve to an intermediate position both gears are released from the shaft, and the machine may in that way be stopped or power may be removed from the gearing. The sleeve might be shifted to this intermediate position when coasting down an incline 20 and then shifted to either gear-wheel, accordingly as greater or less speed is required, when power is again applied to the impelling mechanism. As a means for shifting the sleeve a spanner 18 is provided. This is secured to a suitable sliding shaft 19, loosely held in guides 20 20 on the frame B of the vehicle. This sliding shaft may be shifted back and forth in the guides, causing the spanner to bring the sleeve to any one of the three positions indicated by means of a bell-crank 21, one end of which is pivotally connected to the sliding shaft 19 and the other end secured to a rod 22, leading forward and suitably connected to a lever 23 within easy 30 reach of the operator. The bell-crank lever is suitably pivoted at its angle 24 to the frame B. Thus it will be seen that when the operator moves the lever 23 to a rearward position the bell-crank lever will force the sliding rod to the left in the drawings and cause the clutch mechanism to key the gear-wheel 8 to the driving-shaft 7, throwing in the smaller gear. A reverse extreme movement 35 will of course throw in the larger gear 9, and when the lever 23 is in an intermediate position neither gear will be clutched, as in coasting, for instance. Any suitable brake mechanism may be used, and as such mechanism forms no part of my invention I have not 40 shown it in the drawings.
- 45 In Fig. 5 is shown a slight modification in the gearing of my device. In this view I dispense with the two speed-gears 4 and 5 and employ instead a single gear 50 of any desirable size, mounted centrally on shaft 1 and equidistant between the cranks 22. A gear-wheel 51 is mounted centrally on driving-shaft 7 and adapted to turn loosely thereon. These two gears are in mesh. Gear 51 is provided with the grooved rim, upon which is received the clutch-band engaged by jaws, 50 which latter are operated by means of the wedge-shaped-faced arm sliding on the shaft 7, as before explained. A fork 25 is journaled on the shaft 7—that is to say, the two 70 legs of the fork pass astride the shaft—the ends of the fork being closed to act as a stop to prevent the withdrawal of the fork from the shaft. This fork is located between and in contact with the sliding sleeve 15 and an 75 abutment 53, formed on the shaft 7, the fork adapted to be reciprocated longitudinally on the shaft. The faces of the legs of the fork which contact with the abutment or stop 53 are perfectly plane; but their opposite faces 80 40 40 are of cam-shaped form, located on either side of slot 39 in the fork, through which slot shaft 7 extends, the cam-surfaces extending longitudinally of the fork. These cam-surfaces are highest in the center and taper 85 down gradually at their ends, which merge into the plane of the fork. A stop 41 is formed at the inner end of the fork, and a rod 38 is connected to the inner end of the fork. The fork 25 is normally in a position on the shaft 90 7 intermediate the ends of the cam-surfaces, the length of movement of the fork being determined by the length of the slot 39. In this position the cam-surfaces have forced the sliding sleeve 15 with its wedge-faced arm 29 95 between the ends of pivoted jaws 11 and caused them to tighten the band 12 on the disk 10, thus keying the gear-wheel 51 to shaft 7 and transmitting motion thereto. When the fork 25 is being drawn into this intermediate position, the longitudinal cam-surfaces 40 40 on either side of slot 39 engage the end of sleeve 15, the opposite faces of the fork sliding longitudinally against the stop 53, and as the fork is drawn farther along toward the 100 center of the slot 39 the increasing convexity of the cam-surfaces forces the sliding sleeve 15 laterally along the shaft 7 against the tension of spring 31 until the band 12 is tight on disk 10, as above described. The fork 25 105 may be forced in either direction from its intermediate position to release the gear-wheel 51 from shaft 7, the spring 31 forcing the sliding sleeve 15 and its arm 15' out from between jaws 11. The enlargement 41 contacts 110 with sleeve 15 when the fork is forced to its outward limit of movement and acts as a stop to prevent the wearing out of the fork or lengthening the slot at that end. A similar abutment might be placed at the opposite end 115 of the fork, if found desirable. The fork 25 is connected by a rod 38 to an arm 55 on the shaft 56, journaled in the frame and prevented from endwise movement in any suitable manner. This shaft 56 has an arm 57 secured thereto, from the free end of which a rod 58 extends forward to any suitable lever-arm 23, whereby to operate the fork 25. Of course the fork used in this connection might have the cam-surfaces shorter than those 120 125 shown—that is to say, the cam-surfaces would not need to be formed in a compound curve, 130

but might be of a length just half as great, stopping abruptly at their highest point at the inner end of the slot.

The operation of my invention may be gathered from the description, and further detail is thought to be unnecessary.

It is evident that other slight changes might be resorted to in the form and arrangement of the several parts described without departing from the spirit and scope of my invention, and hence I do not wish to limit myself to the exact construction herein set forth; but,

Having fully described my invention, what I claim as new, and desire to secure by Letters Patent, is—

1. The combination with a shaft or axle and a wheel mounted loosely thereon, the wheel provided with a rim on one of its faces, of an individual clutch-band surrounding and continually supported by the rim, movable means located on the shaft or axle, a pair of jaws engaging the clutch-band, the jaws pivotally supported on a bracket, the bracket being independent of the clutch-band, the movable means adapted to engage the jaws whereby the clutch-band is tightened upon the rim.

2. The combination with a shaft or axle and a wheel loosely mounted thereon, the wheel provided upon one of its faces with a circular rim, of a clutch-band borne upon and entirely supported by the rim, a movable member mounted on the shaft or axle, an upstanding wedge-faced lug on the movable means, a bracket independently secured to the shaft or axle, jaws pivotally secured to the bracket, the forward ends of the jaws engaging the ends of the clutch-band, the wedge-faced lug received between and adapted to spread the rear ends of the jaws whereby to cause the forward ends to clamp the clutch-band to the rim and automatic means for returning the movable member to its normal position when it is desired to release the clutch-band from the rim.

3. The combination with a shaft or axle, and wheels loosely mounted thereon, the wheels each provided on its inner face with a circular rim, of clutch-bands held yieldingly thereon, a sleeve keyed to slide on the shaft or axle, the sleeve having arms on its ends provided with wedge-shaped faces, pivoted jaws likewise mounted on the shaft the jaws engaging loops on the clutch-bands, and adapted to be engaged in turn by the arms carried on the sleeve to force the clutch-bands to grip the rim when the sleeve is shifted toward the wheel to be clutched to the shaft or axle, and means for shifting said sleeve on the shaft or axle.

4. The combination with a shaft or axle, gear-wheels mounted loosely thereon, one of the gears being larger than the other, and circumferentially-grooved rims secured to the gear-wheels, of clutch-bands received in the grooves, the free ends of the bands projecting outward from the peripheries thereof, the

free ends having loops formed therein, pivoted jaws supported on the shaft, the ends of the jaws entering the loops, a sliding sleeve 7c keyed to the shaft and provided with arms having inclined faces, the arms adapted to engage the opposite ends of the jaws whereby to grip the clutch-bands on the rims and lock the gear-wheel to the shaft or axle. 75

5. The combination with a shaft or axle, a plurality of wheels loosely mounted thereon, and clutch mechanism whereby the wheels may be locked to the shaft or axle, of a sleeve keyed to slide on the shaft, means on the sleeve adapted to actuate the clutch mechanism, a spanner for operating the sleeve, a movable shaft to which the spanner is secured, and means for operating the movable shaft whereby the sleeve may engage either one of 85 the wheels or may be assumed an intermediate position.

6. The combination with a shaft or axle, a plurality of wheels loosely mounted thereon, and clutch mechanism whereby the wheels 90 may be locked to the shaft or axle, of a sleeve keyed to slide on the shaft means on the sleeve adapted to actuate the clutch mechanism, a spanner for operating the sleeve, a movable shaft to which the spanner is secured, 95 guides for retaining the movable shaft, a lever secured to the shaft, a rod secured to the free end of the lever, the rod operated by suitable means whereby the sleeve is caused to engage or disengage the clutch mechanism 100 from the wheels.

7. The combination with a shaft or axle, a plurality of wheels loosely mounted thereon, and clutch mechanism whereby the wheels may be locked to the shaft or axle, of a sleeve 105 keyed to slide on the shaft means on the sleeve adapted to actuate the clutch mechanism, a spanner for operating the sleeve, a sliding movable shaft to which the spanner is secured, guides in which to retain the sliding movable shaft, a lever pivoted to the frame, one arm of the lever secured to the sliding shaft and the other arm attached to a rod secured to the free end of the lever, the rod operated by a lever whereby the sleeve 115 is caused to engage or disengage the clutch mechanism from the wheels.

8. The combination with a shaft or axle and a wheel loosely mounted thereon, of clutch-rims secured to the wheel, clutch-bands surrounding and operating on the rims, pivoted jaws engaging the clutch-bands, an arm for actuating the jaws, a sliding sleeve to which the arm is connected, a movable spanner which bears against the sliding sleeve when 120 forcing the arm into engagement with the pivoted jaws, and tension devices against which the arm is moved.

9. The combination with a shaft or axle and a wheel loosely mounted thereon, of clutch-rims secured to the wheel, clutch-bands surrounding and operating on the rims, pivoted jaws engaging and operating the clutch-bands, an arm for actuating the jaws, the

arm mounted upon a sliding sleeve, a spanner located on and actuating the sliding sleeve to force the arm into engagement with the pivoted jaws, and actuating means for operating the spanner whereby the sliding sleeve is reciprocated.

5 In testimony whereof I have signed my

name to this specification in the presence of two subscribing witnesses.

FRANCIS J. STALLINGS.
